UNITED STATES PATENT OFFICE.

ANNA NICODEMUS, OF CHICAGO, ILLINOIS.

CHILD'S GARMENT.

Application filed January 14, 1924. Serial No. 685,941.

To all whom it may concern:

Be it known that I, ANNA NICODEMUS, a citizen of the United States, residing at Chicago, in the county of Cook and State of Illinois, have invented a certain new and useful Improvement in Children's Garments, of which the following is a specification.

My invention relates to an improvement in children's garments, and particularly to a child's garment which is adapted to cover the upper part of the body and to support the clothing for the lower part of the body. One object is to provide such a garment which will be simple and cheap to manufacture. Another object is the provision of such a garment in which the downward pull of the nether garments tends to draw the arm or shoulder bands inwardly toward the neck and to keep them positioned on the child's shoulder. Another object is to provide a garment in which there is no possibility of binding under or about the arms no matter how tight the garment may be elsewhere. Another object is to provide a garment with no buttons on front or back except the supporting buttons on which the nether garments are secured. Other objects will appear from time to time in the course of the specification and claims.

I illustrate my invention more or less diagrammatically in the accompanying drawings wherein:

Figure 1 is a view of the extended finished garment showing all parts of it;

Figure 2 is a view of the blank from which the rear of the garment is formed;

Figure 3 is a side view illustrating the garment as buttoned;

Figure 4 is a section on an enlarged scale on the line 4-4 of Figure 1; and

Figure 5 is a section on an enlarged scale along the line 5-5 of Figure 1.

Like parts are illustrated by like characters throughout the drawings and specification.

A is the back of the garment and is formed from the blank A¹ of the Figure 2, and is indented at the center as at A² to form the spaced, substantially vertical edges A³, A⁴.

In forming the finished garment the lower portion of the blank A¹ is folded together until the edges A³, A⁴ meet and over-lap, the upper portion of the blank being folded to form the pleats B, B¹ which terminate at the shoulder at B², B³.

The edges of the blank are turned in at

the lines A⁵, A⁶ and sewed along the seams C, C¹ providing a broad area along the side of the garment of doubled cloth.

Finally the belt strip D is sewed along 60 the bottom of the rear of the blank, serving to hold the garment in permanent shape, to reinforce it, to prevent pulling out of the darts and to support the buttons.

On the rear of the garment there are three 65 pairs of buttons, each button being secured by a tape which is sewed into the belt.

I prefer to provide a center pair of buttons E adjacent the meeting of the darts B, B¹ with the belt D, and a side pair of buttons E¹, E² sewed into each end of the belt. The top of the belt is turned over and sewed as at E³, and the tapes of the upper buttons E are caught under and held by the seam sewed therethrough. The edges of the garment 75 may be bound with any suitable binding, G.

As a supplemental fastening means to hold the garment secure under the arm pits, I provide any suitable fastening means herein shown as snaps H, H¹.

The front I of the garment is in general similar to the rear, except that the blank of which it is made has no indentation or cut-away portion, and is not provided with pleats or gores, and only one pair of buttons J is provided, that being in the center of the front. The belt portion J¹ is provided at each end with button-holes J², J³ which serve to permit the passage of the buttons E¹, E² of the rear portion of the garment.

The tabs K, K¹ may be sewed into the belt to serve as attaching means for garters.

It will be realized that while I have illustrated a practical and efficient garment, nevertheless many changes might be made in size, shape, proportion or parts and in securing means without departing from the spirit of my invention and I do not wish to limit myself to the specific form herein shown.

The use and operation of my invention are as follows:

The whole garment might be made of one blank shaped like the blank of Figures 3 and 4, joined together at the shoulder straps. It is preferable, however, to make it of two blanks so that the top or center of the shoulder strap is inclined at substantially the angle of inclination of the child's shoulder. Owing to the shaping or inclination of the exposed end or shoulder strap edges of the two blanks, the front blank is

unbroken and is broader or wider than the rear blank. Its edges are inturned and sewed, both to strengthen the garment and to provide a protection beneath the arm and down the side of the garment. The rear blank is first centrally folded to bring the edges together and these edges are then sewed; the loose folds of cloth thus formed are then folded over to form the pleats which incline from the center portion of the rear blank upwardly toward the shoulder and terminate in the shoulder bands. The button supporting belt pieces are then sewed in place on both the front and rear blanks, and a vertically aligned pair of buttons is secured to the center of each blank and to each end of the belt of the rear blank, the straps or tapes on which the buttons are mounted being preferably sewed into the belt sections. In order to grip the second button the top of the belt blank is re-folded and sewed along the central belt seam. The pleats extend upwardly and outwardly from the center button pair of the rear blank. It is this button pair upon which the maximum strain or weight is applied and the tendency of the weight and tension of the nether garments is thus to pull down on the pleats. These pleats direct the tension upwardly to the shoulder straps and the direction of the tension is such that the straps

tend to be drawn inwardly and upwardly on the shoulder and resist the usual tendency of the shoulder straps to escape from the shoulder and permit the usual type of garment to waist to drop. The two blanks are joined at the shoulder straps permanently. I provide button holes at the ends of the belt of the front blank so that the end belt buttons of the rear blank serve not merely for the support of the nether garments, but also serve as means for joining the front and the rear blanks at the belt. I also provide a snap at the bottom of the arm hole on each side to keep the two sides or blanks of the garment together.

I claim:

In a garment, a front portion and a rear portion, and shoulder straps connecting them, and means for securing the front and rear portions together beneath the arms to close the garment, and a pair of pleats extending upwardly from a point in the middle of the rear portion of the garment and adjacent the bottom thereof, to the shoulder straps, and clothes supporting means situated at a point adjacent the convergence of said pleats.

Signed at Chicago, county of Cook and State of Illinois, this 4th day of January 1924.

MRS. ANNA NICODEMUS.
